[57] CLAIM

The ornamental design for a pet bed, as shown and described.

DESCRIPTION

FIG. 1 is an isometric view taken from the top, front and right side of a pet bed showing my new design; FIG. 2 is a front elevational view thereof; FIG. 3 is a rear elevational view thereof; FIG. 4 is a right side elevational view thereof, the left side being a mirror image of the right side shown; FIG. 5 is a top plan view thereof; FIG. 6 is a bottom plan view thereof; FIG. 7 is another isometric view thereof with the canopy removed for convenience of illustration; and FIG. 8 is an isometric view taken from the top, front and right side of a modified form of the pet bed shown in FIG. 1.
